BOTTLE

Arnold I. Lorenzen, Toledo, Ohio, assignor to Owens-Illinois Glass Company, Toledo, Ohio, a corporation of Ohio

Application October 11, 1957, Serial No. 48,068

Term of patent 14 years

(Cl. D58—8)

Fig. 2.

Fig. 1 is a side elevational view of a bottle showing my new design, the surface decoration illustrated being repeated on the other side of the bottle.

Fig. 2 is a fragmentary sectional view taken at the line 2—2 of Fig. 1 to indicate that the bottle is of cylindrical form.

I claim:

The ornamental design for a bottle, substantially as shown and described.
